STENCILING APPARATUS

Harold R. Schutz, Toledo, Ohio, assignor to Libbey
Glass Company, a corporation of Ohio

Application August 20, 1936, Serial No. 96,993

4 Claims. (Cl. 101—124)

The present invention relates to stenciling apparatus designed for use in applying a vitreous enamel composition or paint to articles of glassware such as tumblers, jars, bottles and the like, and to other articles of a vitreous or ceramic nature in the lettering or decorating thereof by a stenciling process.

While the invention may well be employed where either the screen or squeegee is moved positively it relates to stenciling apparatus of the type employing a reciprocable stencil screen capable of movement relative to the article undergoing decoration and having permeable portions through which the decorating material is transferred to the article by the spreading action of a squeegee which is maintained in contact with the screen along the line of contact between the screen and surface of the article undergoing decoration.

In apparatus of this type, it is necessary that, upon completion of each stenciling operation and prior to movement of the screen to either of its extreme positions, the squeegee be elevated momentarily from the screen to clear the enamel composition thereon in order that a quantity thereof may be passed under the squeegee and occupy a position on the screen in advance of the squeegee immediately prior to return movement of the screen in the performance of the next succeeding decorating operation.

Heretofore in apparatus of this type, this clearing operation has been dependent upon the skill and judgment of the operator who has been obliged to approximate the proper moment in each stroke of the reciprocable stencil screen for elevating the squeegee to clear the enamel composition on the screen. When this relatively important clearing operation is left entirely to the skill of the operator, neither uniformity of design nor maximum output can be attained. Accordingly, the principal object of the invention is to provide an automatic means for momentarily elevating the squeegee from the stencil screen at the completion of each individual decorating operation but prior to movement of the stencil screen to either of its extreme positions.

Other objects and advantages of the invention will appear hereinafter.

In the accompanying drawings:

Fig. 1 is a top plan view of a stenciling apparatus manufactured in accordance with the principles of the present invention;

Fig. 2 is a side elevational view of the apparatus shown in Fig. 1;

Fig. 3 is an enlarged fragmentary top plan view

of a portion of the apparatus shown in Fig. 1 and showing an automatic trip mechanism employed for elevating the squeegee;

Fig. 4 is a side elevational view of the fragmentary showing made in Fig. 3;

Fig. 5 is a side elevational view similar to Fig. 4 showing the various parts thereof in another position;

Fig. 6 is a transverse sectional view taken substantially along the line 6—6 of Fig. 1; and

Fig. 7 is an enlarged fragmentary sectional view, diagrammatic in its representation, taken transversely through the article undergoing decoration, the stencil screen, and a portion of the squeegee, showing the manner in which the elevated squeegee clears the enamel composition on the stencil screen.

The apparatus involves in its general organization a base 10 in the form of an elongated, substantially rectangular casting provided with a recess 11 in the forward side thereof medially of its ends. Bolted or otherwise secured to the base 10 on opposite sides of the recess 11, and extending vertically upward therefrom, are a pair of standards or supports 12 (Fig. 2) having integrally formed aligned bearings 13 medially of their ends which serve to support therebetween a horizontal rock-shaft 14 (Fig. 6).

An article supporting assembly 15 (Figs. 2 and 6) is pivotally mounted on the rock-shaft 14 and is designed to rotatably support thereon a tumbler T or like article to be decorated. The lower portion of the article supporting assembly 15 extends into the recess 11 and the entire assembly is adapted by an automatic mechanism, not shown, and which forms no part of the present invention, to be swung about the axis of the rock-shaft 14 to a lowered position to facilitate insertion of an undecorated article in the apparatus or the removal of a decorated article therefrom.

A pair of supporting members 16 (Figs. 1 and 2) each having a forwardly and upwardly extending supporting arm 17, and a vertically extending supporting arm 18, are bolted or otherwise secured to the base 10 at opposite ends thereof. A pair of front and rear, transversely extending, horizontal tracks 19 and 20 respectively, are carried by the supporting arms 17 and 18 and are substantially coextensive with the base 10.

Supported tractionsally upon the tracks 19 and 20 and movable therealong in either direction transversely of the apparatus, is a stencil screen carriage 21 having associated therewith a stencil screen S adapted to occupy a position in the apparatus in tangential rolling line contact with

the article T supported in the assembly 15 therebeneath. The stencil screen carriage includes supporting wheels 22 which ride upon the tracks 19 and 20 and which are mounted on the parallel 5 side bars 23 of the carriage 21.

The upper ends of the standards 12 are provided with integral guides 24 (Fig. 1) having axially aligned bores 25 which serve to support therebetween a horizontal rock-shaft 26. A 10 squeegee arm 27 is rockably mounted on the rock-shaft 26 by means of an integral sleeve 28 formed on the rear end of the arm 27 and through which the shaft 26 extends. The squeegee arm 27 extends over the tracks 19 and 20 and the forward 15 end thereof is supported on the front track 19 by means of an adjusting screw 29 which bears on the track 19 and by means of which a squeegee S' carried by the arm 27 may be adjusted to the screen S. The extreme forward end of the 20 arm 27 is turned downwardly as at 27' in close proximity to the track 19.

Upon movement of the carriage 21 from the extreme position shown in Fig. 1 to a corresponding position on the opposite side of the apparatus, or vice versa, the squeegee S' which bears lightly against the screen S along the line of contact between the tumbler T and the screen S, forces coloring material, which is placed on the screen S, through the screen and onto the tumbler T with which it makes tangential rolling line contact.

Referring now to Figs. 2, 3, 4, and 5, an automatic trip mechanism for momentarily elevating the squeegee arm 27 and squeegee S' carried thereby, from the stencil screen S is shown. The trip mechanism is adapted to function after the complete design has been applied to the tumbler T but prior to movement of the carriage 21 to either of its extreme positions. Such momentary 40 elevation of the squeegee S' permits the enamel composition on the screen to pass under the squeegee and occupy a position ahead of the squeegee during the return stroke of the carriage in order that proper application of the design 45 may be made to the next succeeding tumbler undergoing decoration.

Pivoted to the stationary front track 19 in the vicinity of the squeegee arm 27 and on opposite sides thereof, are a pair of fingers 30 which normally extend upwardly into the path of the carriage 21 and which are adapted to be engaged by the extreme ends of the respective side bars 23 upon approach of the carriage 21 to one or the other of its extreme positions. Each of the fingers 30 is connected through links 31 to one arm of a bell crank lever 32. The other arm of the bell crank lever 32 is conveniently curved for engagement with the underneath side of the downwardly turned end 27' of the squeegee 60 arm 27.

It will be seen that inward swinging movement of either of the fingers 30 toward the squeegee arm 27 will transmit motion through the respective links 31 and bell crank levers 32 in such a manner as to elevate the forward end of the arm 27 to permit the squeegee S' to clear the enamel composition on the screen S. Each of the fingers 30 is maintained in its upwardly projecting position by means of a coil spring 35 connected 70 at one end to some stationary point on the track 19 and at the other end to a medial point on one of the fingers 30. The tension of the springs 35 is insufficient to raise the squeegee arm 27 from its supported position on the front track 19.

75 Upon completion of the decorating operation,

i. e., after the completed design has been applied to the tumbler T, as the carriage approaches the end of its stroke at either end of the track 19, the forward end of one or the other of the shafts 23, as the case may be, passes completely over its respective finger 30 and in so doing, tilts the finger inwardly as shown in Fig. 5 toward the arm 27 to momentarily raise the arm in the manner just described.

Upon passing beyond the radial limits of the 10 finger 30, the end of the shaft 23 releases the finger 30 which is immediately returned to its upright position as shown in Fig. 4, thus permitting the squeegee S' to return by gravity to screen engaging position. Upon commencement of the 15 next succeeding decorating operation, as the carriage 21 is moved in the reverse direction, the end of the shaft 23 trips lightly over the finger 30 with no significant effect other than to permit the carriage to continue its unobstructed move- 20 on the tracks 19 and 20.

In Fig. 7, the squeegee S' is shown in the elevated position which it momentarily assumes upon tripping of the mechanism just described. A portion of the enamel composition on the screen 25 S has passed with the screen underneath the squeegee and, upon lowering of the squeegee into contact with the screen, this enamel composition will occupy a position ahead of the squeegee for proper application to the tumbler T during the 30 next operative decorating movement of the screen carriage 21.

Modifications and variations may be resorted to within the spirit and scope of the appended 35 claims.

I claim:

1. The combination with a stenciling apparatus including a horizontally disposed track, a stencil screen carriage mounted on said track for reciprocation from one end thereof to the other, a 40 stencil screen on the carriage, means for positioning an article having a curved surface to be decorated in tangential rolling line contact with said screen, and a squeegee normally in contact with said screen for forcing decorating material 45 through the same onto said article, said squeegee being adapted to be lifted out of contact with said screen, of an automatic trip mechanism including a finger projecting into the path of movement of said carriage and adapted to be engaged by 50 said carriage as the same approaches the end of its stroke in one direction, a lifting finger for lifting said squeegee, and a link connecting said fingers.

2. The combination with a stenciling apparatus 55 including a horizontally disposed track, a stencil screen carriage mounted on said track for reciprocation from one end thereof to the other, a stencil screen on the carriage, means for positioning an article having a curved surface to be 60 decorated in tangential rolling line contact with said screen, and a squeegee normally in contact with said screen for forcing decorating material through the same onto said article, said squeegee being adapted to be lifted out of contact with said 65 screen, of an automatic trip mechanism including a finger pivoted to said track and projecting into the path of movement of said carriage, a bell crank lever pivoted to said track, one arm of said lever being in the form of a lifting finger adapted 70 to engage said squeegee to lift the same out of contact with said screen, and a link connecting the other arm of said bell crank lever and said first mentioned finger.

3. In a stenciling apparatus, a reciprocable 75

stencil screen movable in its own plane from an extreme position on one side of the apparatus to a corresponding extreme position on the other side of the apparatus, means for positioning an article having a curved surface to be decorated 5 in tangential rolling line contact with said screen, a squeegee mounted for tilting movement about a horizontal axis, said squeegee being normally in contact with said screen and being adapted upon reciprocation of the latter to force coloring 10 material through the screen and onto the article undergoing decoration, said squeegee being adapted upon tilting movement thereof to move out of contact with said screen, a finger projecting into the path of movement of said carriage 15 and adapted to be engaged by said carriage as the same approaches the end of its stroke in one direction, a lifting finger adapted to engage the free end of said squeegee to elevate the same and

tilt the squeegee about said axis, and a link connecting said fingers.

4. In a stenciling apparatus, a horizontally disposed track, a stencil screen carriage mounted on said track for reciprocation from one end thereof to the other, a stencil screen mounted on said carriage, means for positioning an article having a curved surface to be decorated in tangential rolling line contact with said screen, a squeegee 10 normally in contact with said screen for forcing 15 decorating material through the same onto said article, said squeegee being adapted to be lifted out of contact with said screen, a squeegee lifting element pivoted to a stationary part of the apparatus adjacent said track and adapted to be moved into lifting engagement with said squeegee, and a finger connected to said element and projecting into the path of movement of said carriage.
